UNITED STATES PATENT OFFICE.

CHARLES F. SCHWENNKER, OF SCHENECTADY, NEW YORK, ASSIGNOR TO GENERAL ELECTRIC COMPANY, A CORPORATION OF NEW YORK.

SAFETY SWITCH.

Application filed March 30, 1922. Serial No. 548,121.

The present invention relates to electric switches, and more especially to safety or enclosed switches for power purposes.

Where electric power is employed for driving industrial apparatus, such as machine tools, it is necessary for the operative to be able to freely control the supply of power current thereto, and on account of the dangerous character of such power currents it has become customary to enclose the fuses, switches and their connections in iron boxes with only the insulated operating handle accessible to the operative. These enclosures or boxes are provided with seals and locks so that they may not be opened except by a duly authorized party, and as they must be opened whenever a fuse is to be renewed it is desirable that they be made to afford protection to the authorized party while making such renewals by arranging the box lid so that the fuses and their holders only are exposed when the lid is open, and the switch is so interconnected with the lid that the electric current is cut off from those parts whenever the lid is moved out of its closed position.

The object of my invention is to provide an improved safety switch which shall be hardy, highly efficient and compact, which will permit one portion of its cover to be raised for safe renewal of fuses while the other portion remains fixed over the switch mechanism or permit both portions to be raised as a unit without being detachable from each other or from the box, to permit of repair or renewal of the switch mechanism, and which when closed will be rain-shedding.

One embodiment of my invention is shown in the accompanying drawings, in which Fig. 1 is a perspective view of the safety switch with the lid in raised position; Fig. 2 is a similar view with the whole cover in raised position; Fig. 3 is a front elevation with part of cover broken away to show the switch construction; Fig. 4 is a vertical section taken on line 4-4 of Fig. 3 with the switch in closed position; Fig. 5 is a similar fragmentary section with the switch in open position; Fig. 6 is a right side elevation of the switch handle and associated parts shown

in closed position; Fig. 7 is an exploded perspective view of the switch handle and associated parts; and Figs. 8 and 9 are fragmentary sections showing detail of pivotal support for the cover.

The casing or box is made up of heavy sheet steel punchings comprising a main portion 1 forming the back and two sides, an upper detachable end portion 2 with a flange 3 on three sides and adapted to fit down outside the back and two sides of the main portion 1, and a lower detachable end portion 4 having a flange on three sides adapted to fit within the back and two sides of the main portion. These parts are held together by screws or other retaining means 5. The cover comprises a normally fixed or upper member 6 and a transversely hinged lower member or lid 7. Both members have flanges 8 on three sides adapted to overlap the sides and ends of the box, while adjacent the meeting edges of the members the flanges 8 are pivotally connected by rivets 9 and in such manner that the edge of the hinged member 7 underlies the adjacent edge of the upper member 6, so that when the former member is closed the joint between them will shed water. The upper end portion 2 has a gutter 2', Fig. 6, serving to divert the water from entering the box.

The upper member 6 is mounted on the box by means of a pivotal bracket 10 having angular end portions 11 terminating in hooked tips 12. These end portions are riveted to the inside of the upper member 6 and their hooked tips 12 extend freely through slots 13 in the left side of the box body and are assembled by a forward longitudinal movement therein to hook over the lower end walls of said slots 13 and there locked by arranging the latter relative to the end of the box body that the flange 3 of the upper box end 2 upon being connected to the main box portion engages the adjacent tip 12 and holds it and its companion in depressed position. By means of this pivotal bracket the entire cover may be swung out to full open position without interference between the box side and the adjacent portion of the flange 8, and there arrested by the angular central part of the bracket en-

gaging with the box side as is indicated in Fig. 2. The means for fastening the upper cover member in closed position consists of a hasp 14 hinged to the side opposite the pivotal bracket by a lug 15 riveted to the inside of the right-hand flange 8 thereof and provided with a shoulder 16 adapted to engage the inner surface of the hasp and prevent its swinging inwardly sufficiently to enter the box when the cover is being closed. The free end of the hasp is provided with the customary slot 17 for the reception of the lug or staple 18 fixed on the side of the box and adapted to receive a padlock. The lower edge 19 of the hasp is made cam-shape for a purpose to be set forth later. The means for fastening in closed position the lower cover member or lid 7 consists of a pierced lug 20 extending outward from the edge of the lower end 4 of the box and adapted to pass through a slot 21 formed in the free edge of the lid and to receive a seal or other securing means. Near the hinged side of the lid is riveted an extension or heel plate 22 having a shoulder 23 arranged to engage the side of stop 24 (see Fig. 3) pivoted to a bracket 25 on the inner side of the box and adapted to be swung out by hand when it is desired to temporarily retain the lid in raised position.

Within the box is detachably mounted by means of screws 26 a combined switch and fuse cutout comprising an insulating base 27 having mounted thereon beneath the lid 7 pairs of aligned fuse clips 28 and beneath the upper portion 6 of the cover corresponding switch pivot clips 29 and contact clips 30, in cooperation with which are switch blades 31 rigidly connected at their free ends by an insulating bar 32. To this bar are rigidly secured by bolts 33 two stiff spring yokes 34, the inner ends 35 of which are bent backward and adapted to strike against the insulating base 27 and cushion the hammer blow incident to closing of the switch, while the opposite ends 36 are bent backward and upwardly into elbows for free engagement with the switch-actuating rod 37 and serve to cushion the outward thrust of the switch upon opening. In case it should become necessary to replace the combined switch and cutout, it is necessary only to remove the screws 26 and draw it upwardly from beneath the actuating rod 37.

The actuating rod 37 is bow-shaped and pivoted at one end in the left side of the box somewhat in front of the axis of the pivots of the switch blades 31 and at the other end in an axial bore 38 in the crank shaft 39 where it may be fastened by a cotter pin through the latter. The bowed part of the actuating rod 37 rests freely in the elbows 36 when the switch is in normal closed position and hugs the elbows when the switch is in the normal open position as is indicated

in Figs. 4 and 5 on account of the relative eccentricity of the actuating rod and the pivotal axis of the switch blades and thereby operates to yieldingly arrest the outward movement of the latter.

The means for operating the switch-actuating rod 37 comprises a crank 40 rigidly mounted on the outer end of the shaft 39 journalled in the right-hand side of the box and in which the rod is adapted to rock independently thereof to provide for a certain lost motion between them. The inner end of the shaft 39 has a portion of its cylindrical wall cut away to provide a V-shaped notch 41, between the sides of which the bent portion of the rod extends outwardly and with which it alternately engages when the crank 40 is moved from one position to the other.

The means for causing the switch to move with a snap action comprises a spring 42 surrounding a thrust bar 43 threaded through an angular end of the bracket 25 and pivoted to a lug 45 on the inner end of a U-shaped wrist plate 44 made of sheet metal and journalled upon the inner end of the crank shaft 39 with its outer end bearing against the inner adjacent wall of the box side while the opposite end 45 is formed about the rod 37 to positively lock them angularly together, so that when the rod 37 has been rocked by means of its connection with the crank 40 sufficiently to carry the pivotal point between lug 44 and the thrust rod 43 past its dead center the spring 42 is free to react and throw the switch-actuating rod 37 and with it the switch blades 31 to their extreme position.

The interlocking means whereby the switch is required to be opened before opening of the box lid and also prevented from closing while the lid is out of its closed position comprises arc-shaped keepers 46 and 47 struck up from a sheet metal plate 48 rigidly connected to the inner side of the crank 40 and adapted to contact with the heel plate 22 of the lid. A stop plate 49 is riveted to the side of the box and has a bearing aperture 50 aligning with the bearing aperture in the box for the reception of the crank shaft 39, arcuate stop flanges 51 and 52 at its upper and lower edges and its right-hand end bent outwardly to form the staple 18. The arcuate keeper 46 and the stop flange 51 are provided with abrupt ends and so disposed with relation to each other that they operate to arrest the crank 40 at the end of its travel in either direction. When the lid is in open position the bent tip 53 of the heel plate stands in the path of the upper end of the keeper 46 and locks the crank 40 in the left or off position. When the lid is closed the tip 53 of the heel plate is swung up above the path of the keeper 47 and the latter travels beneath it throughout

its movement so that the lid is held down thereby whenever the crank is out of its full off position.

In order to prevent the hasp 14 being raised while the crank 40 is out of its full off position, the plate 48 is provided with a radial finger 54 which overlies the adjacent cam-shaped edge 19 of the hasp 14 during such positions of the crank.

10 In order that the cover may be held in fixed relation to the box mouth while closed and thereby to insure the alignment of the hasp 14 with the parts cooperating therewith, I provide a notch 15' in the edge of 15 the right-hand side of the box in position to receive therein the lug 15 of the cover.

In order that the switch may be locked in its off position, the arcuate stop flange 52 has a slot 55 adapted to receive one or more 20 padlocks which will extend into the path of swing of a stop shoulder 56 formed on the crank 40.

In case a fuse is to be renewed the switch will first be thrown to off position by pulling 25 crank 40 down to the position indicated in Fig. 1, the seal or other fastening means removed from the lug 20 and the lid 7 raised and there secured by swinging the stop 24 outwardly behind the shoulder 23 on the heel 30 plate 22. The switch is automatically locked in off position by the tip 53 of the heel plate standing in the path of the upper end of the keeper flange 46. The party renewing the 35 fuses may then insert his hand within the box without danger of shock since all accessible parts are dead, the only live parts being the upper switch clips 30 to which the line wires connect, and they are too remote to be reached.

40 In case it becomes necessary to inspect, repair or replace the switch, the padlock securing the hasp 14 to its staple 18 must be removed by an electrician or other duly authorized party having the key thereto. The 45 crank 40 must be pulled down to the full off position to remove its radial finger 54 from the path of outward swing of the hasp 14, as indicated in Fig. 1, then upon raising the hasp the entire cover is free to swing back 50 and be there supported normal to the box by the pivotal bracket 10 as indicated in Fig. 2. In this position of the cover all parts within the box are freely accessible and the switch may be opened and closed without interference of the interlocking means between 55 lid 7 and crank 40.

The Patents 1,524,801, February 3, 1925 and 1,527,709, February 24, 1925 are divisions hereof.

60 While I have shown and described the best embodiment of the invention known to

me, I do not desire to be restricted thereto.

What I claim as new and desire to secure by Letters Patent of the United States, is:—

1. In an electric switch, the combination 65 of a metal box having slots formed in one side parallel to the front edge thereof, a flanged cover for said box, a pivotal bracket on said cover having hook-shaped tip portions extending outwardly and adapted to 70 enter said slots from the inside of the box and be interlocked with the wall at the ends thereof by a forward longitudinal movement therein, and means to prevent a return longitudinal movement of said tip portions in 75 said slots.

2. In an electric switch, the combination 80 of a metal box comprising a main portion having longitudinal slots formed in one side parallel to the front edge thereof and an end portion provided with a flange adapted to overlap the side and a part of one of the said slots, a flanged cover for said box, a pivotal bracket on the inside of said cover provided with hook-shaped end portions 85 adapted to freely enter said slots from the inside of the box and interlock with the wall at the ends thereof by a forward longitudinal movement therein, and means for securing the end and main portions of the box 90 together.

3. In an electric switch, the combination 95 of a metal box having slots formed in one side parallel to the front edge thereof, a cover having a flange adapted to overlap the sides of said box, a pivotal bracket on the inside of said cover comprising angular end portions having hook-shaped tips extending outwardly and adapted to freely enter said 100 slots from the inside of the box and be interlocked with the wall at the ends thereof by a forward longitudinal movement therein, and detachable means for engaging one of said end portions to hold it in advanced 105 position.

4. In an electric switch, the combination 110 of a metal box having slots formed in the rear side parallel to and spaced from the front edge thereof, a cover having a peripheral flange adapted to overlap the sides of said box, a pivotal bracket on the inside of said cover independent of said flange and having angular end portions adapted to enter the said slots from the inside of the box and interlock therewith, and the said bracket having an intermediate portion adapted to abut against the inner wall of the said rear side when said cover is in open position.

In witness whereof, I have hereunto set my hand this 29th day of March, 1922.

CHARLES F. SCHWENNKER.
